UNITED STATES PATENT OFFICE.

RICHARD M. STEPHENS, OF IRVING, TEXAS, ASSIGNOR OF ONE-TWELFTH TO CHARLES E. MANLEY AND ONE-TWELFTH TO ELMER L. LIPP, BOTH OF LOS ANGELES, CALIFORNIA.

ELECTRIC WATER HEATER.

1,406,100.

Specification of Letters Patent. Patented Feb. 7, 1922.

Application filed June 23, 1920. Serial No. 391,060.

To all whom it may concern:

Be it known that I, RICHARD M. STEPHENS, of Irving, Texas, have invented certain new and useful Improvements in Electric Water Heaters, whereof the following is a specification.

This invention relates to electric water heaters, adapted for heating small bodies of water, and of the class in which the water itself constitutes the final closing of the circuit.

The invention comprises a heating unit composed of two hollow carbon cylinders, or shells, one within the other, both cylinders being open at their ends, and separated by insulators at the bottom, and by insulating and packing material, at the top. The walls of the cylinders are perforated, so that there may be a free circulation of water through and between them. These carbon cylinders constitute the anodic and cathodic termini of the electric circuit, so that the current may flow from the source through the connections to one of the carbons, then through the water to the other carbon, and back through the connections to the source.

The carbon cylinders are enclosed in a metallic cup, which is deeper than the length of the carbons, and protects them and the user of the instrument. The cup is perforated, except for a portion near its top, and is closed at the top by a combined plug and handle, thus leaving a watertight chamber within the cup, and between the bottom of the plug and handle, and above the carbons, which watertight chamber encloses the connections of the carbons to the conductors. The outer carbon is separated from the cup by insulators at the lower end, and by insulators and packing at the top.

In the accompanying one sheet of drawing I have illustrated an instrument containing my invention.

Figure 1 is an elevation of the complete instrument, the metallic cup being partially cut away at the bottom, to expose the interior.

Figure 2 is a sectional elevation of the instrument.

Figure 3 is a cross-section on line 3, 3, of Figure 2.

Figure 4 is a cross-section on line 4, 4, of Figure 2.

In the figures;— The metallic shell, or

cup, 1, is closed, at the top by the combined plug 3 and handle 4, composed of a non-conducting material. I have found bakelite to be a satisfactory material for this purpose. The cup 1 may be locked to the plug and handle by a bayonet joint, as 5. The side walls and bottom of the cup are perforated, as at 2, except for a portion near the top of the cup, thus permitting a free circulation of liquid therethrough.

Within the cup 1 is a hollow carbon cylinder 6, with open ends, and within this a second hollow cylinder of carbon, 7, also with open ends, both of which are perforated, as at 8 and 9, to permit the free circulation of liquid through and between them, and the outer sides of the outer cylinder 6 are grooved or corrugated, for the same purpose. At the bottom of each carbon cylinder between them and between the outer one and the cup 1, are insulating spacing rings 11, which serve to separate them electrically. Similar rings at the tops perform the same function at that point, but are made of a packing material, so as to form a watertight joint, thus keeping water from passing above them, and the hollow of the inner carbon is plugged for the same purpose. As a leakage of water at the bottom is not material, the insulators there need not be watertight.

The plug and handle, 3, 4, are hollowed, longitudinally, to accommodate the connection conductors, 16, which are connected to the carbons at 17, within the chamber 12, and are thus protected by the chamber.

When repairs are desired, the cup 1 may be given a twist, unlocking the bayonet joint 5, and the cup then pulled off, exposing the carbons and connections and rendering them accessible.

The cup and carbons are maintained in proper relative positions by the connections at 17, and by the friction of the packings at 10, and the packings 10 and insulators 11, and these members may be bedded in circumferential grooves in the carbons, in furtherance of this function.

I claim:—

1. An electric water heating unit, comprising, in combination, a metallic perforated cup, two concentric perforated carbon cylinders, having open ends, within said cup, and of less length than the depth there-

of, said cylinders spaced and insulated from each other and from the cup, by insulators at the bottoms of the carbons, and insulating packings at the top, said carbon cylinders adapted to respectively constitute the anodic and cathodic termini of an electric circuit.

2. An electric water heating unit, comprising, in combination, a metallic perforated cup, two concentric, perforated, carbon cylinders, having open ends, within said cup, and of less length than the depth thereof, insulators spacing and insulating said carbons and cup from each other at the bottoms thereof, and insulators and packing spacing and insulating said members from each other at the tops thereof, said carbons adapted to respectively constitute the anodic and cathodic termini of an electric circuit, and 20 said outer carbon having corrugated sides.

3. An electric water heating unit, comprising, in combination, a metallic cup having a perforated surface except near the top thereof a non-conducting combined plug and

handle attached to said cup at the upper end 25 thereof, and forming a closure therefor, two hollow carbon shells, open at their ends, one within the other, insulating rings spacing said cup and carbons apart at the bottoms thereof, insulating and packing rings spacing said cup and carbons apart at the tops thereof, both said carbon shells being perforated, and of less length than the depth of the cup, the hollow of the inner carbon being closed at the top, and there being a watertight chamber above the carbons and below the plug and handle, and within the imperforate portion of the cup, electric conductors extending through said plug and handle, and connected to said carbon shells 40 within said watertight chamber, said carbons and cup held in place by the electric connections and the friction of the packings.

In testimony that I have invented and claim the foregoing I have hereto set my 45 hand this 1st of June, 1920.

RICHARD M. STEPHENS.
